UNITED STATES PATENT OFFICE.

LOUIS H. PERLMAN, OF NEW YORK, N. Y.

WHEEL.

1,324,617.

Specification of Letters Patent.

Patented Dec. 9, 1919.

Application filed September 23, 1916. Serial No. 121,827.

To all whom it may concern:

Be it known that I, LOUIS H. PERLMAN, a citizen of the United States, residing at New York, in the county of New York and State of New York, have invented certain new and useful Improvements in Wheels; and I do hereby declare the following to be a full, clear, and exact description of the invention, such as will enable others skilled in the art to which it appertains to make and use the same.

This invention relates to improvements in demountable rims of the channel type, and more particularly to that form of such rims as has become known as cross split.

The object in view is the provision of simple and efficient means for locking the ends of the cross split rim together.

A further object in view is the provision of such locking means so constructed as to be adapted to itself serve as a driver.

With these and further objects in view, as will in part hereinafter be specified and in part become apparent, the invention comprises certain novel constructions, combinations and arrangements of parts as subsequently specified and claimed.

In the accompanying drawing,—

Figure 1 is an inverted plan view of a demountable rim embodying the features of the present invention.

Fig. 2 is a transverse axial section taken centrally therethrough, a fragment of a wheel body being seen partly in elevation and partly in section.

Fig. 3 is a transverse section taken approximately on the plane indicated by line 3—3 of Fig. 2, the parts being broken away and seen in section.

Fig. 4 is a detail perspective view of a modified form of clip detached.

Fig. 5 is a circumferential section of a fragment of a rim having applied thereto the form of clip seen in Fig. 4.

Referring to the drawing by numerals, 1 indicates a wheel body having the fixed rim or felly band 2. The felly band 2 is provided with the usual stop flange 3 at the inner face of the wheel.

A demountable rim 4 of the cross-cut channel type is adapted to be mounted on the felly band 3 with the inner edge of rim 4 resting against the flange 3, the outer edge being supported and retained in position by the usual locking wedges or other similar locking means, not illustrated.

The cross-cut of rim 4 provides ends 5 and 6. In the course of construction the base portion of the rim 4 is extended slightly beyond the flanges at the place of the cross cut, so that there are two outstanding end portions of said base and the said outstanding end portions are bent inward to form inwardly extending projections or transverse flanges 7. The bending or stamping of these projections inwardly enables the ends of the rim at the cross cut, including the flanges, to substantially meet, as clearly seen in Figs. 1 and 2 of the drawing. A spring clip 8, preferably of comparatively stiff rigid material, and substantially U-shape in cross section is formed to be forced over the flanges 7. The clip 8 is preferably approximately of the same length as the flanges, and to keep the clip 75 from vibrating loose, the flanges 7 are provided with depressions 9, 9, and the clip is provided with inwardly extending projections 10 adapted to seat in said depressions. The said depressions and projections may be formed in any appropriate manner, as by being stamped.

In operation, the rim 4 is applied to and removed from the wheel body after the manner of any ordinary demountable rim, 85 being rocked on or off in order to accommodate the valve stem as is well understood in this art. By preference, however, the felly band 2 is provided with stop lugs or plates 12, 12, positioned to serve as drivers and to 90 coöperate with the U-shaped clip 8 when in position in engagement with the flanges 7. The plates 12 are spaced apart a distance to snugly receive the said clip therebetween.

When the rim 4 is not mounted on the 95 wheel, and it is desired to interchange a tire it is only necessary to pry the clip 8 away from the flanges 7 as by the use of a screw driver or other appropriate tool, and then the end portions 5 and 6 are free for 100 relative movement. One of the end portions is then sprung beneath the other and either swung laterally and the rim and tire 105 relatively moved with respect to each other similar to an unscrewing movement, or the sprung end of the rim is caused to move to a lapping position with respect to the other end a distance sufficient to reduce the diameter of the rim to that extent necessary to enable the rim to be freely withdrawn from 110 the tire. To replace the new tire it is only necessary to effect a converse movement of

the parts to that employed in removing a tire. Of course, after the tire is in place on the rim and the flanges 7 are in alinement, the clip 8 is applied thereto and the tire is 5 ready for inflation and use.

In Figs. 4 and 5 I have illustrated an embodiment varying slightly from that described in that the clip 8^a is provided with inwardly turned flanges or projections 9^a in 10 addition to the projections 9^b. In this embodiment, it is only necessary to have one set of projections 9^b, as such projections serve merely to prevent longitudinal sliding of clip 8^a. In practice, the flanges 9^a engage corresponding grooves or recesses in the transverse projections 7^a which extend radially inward from the end portions 6^a and 6^b of the rim 4^a. Preferably the ends of flanges 9^a are beveled off, as seen at 9^c, to 15 facilitate application of the clip to the projections 7^a.

What I claim is:

In a wheel structure, a demountable rim

of the channel type having a cross cut, the base portion of the rim being formed into 25 an integral, inwardly extending flange at each end of the thickness of the base, the flanges being shaped to lie contiguous to each other, and a U-shaped spring clip of a length substantially equal to the length of 30 the flanges and adapted to be sprung over and to snugly fit the flanges for retaining the ends of the rim in operative relation, each of the flanges being formed with a recess and the clip being formed with projections adapted to enter said recesses for being retained against dislocation, the recesses of the flanges and the projections of the clip extending longitudinally of the 35 clip.

In testimony whereof I affix my signature in presence of two witnesses.

LOUIS H. PERLMAN.
